TYPEWRITER

Lyman G. Saunders, Detroit, Mich., assignor to
 Burroughs Adding Machine Company, Detroit,
 Mich., a corporation of Michigan

Application June 22, 1934, Serial No. 731,798

7 Claims. (Cl. 197—82)

This invention relates to typewriters and it has to do more particularly with escapement operating mechanism therefor.

One of the objects of the invention is to provide an improved typewriter construction.

Another object is to provide an improved escapement operating mechanism.

A further object is to provide improved space bar mechanism.

10 A more specific object is to provide an improved arrangement wherein both a partial and a full escapement of the carriage takes place upon downward depression of the space bar whereby correct spacing of letters following operation 15 of the space bar is insured.

Other objects and advantages will become apparent as this description progresses and by reference to the drawing wherein,—

Figure 1 is a rear, skeleton-like, perspective view of a machine showing one arrangement of escapement and space bar mechanism in normal position and embodying my invention;

Fig. 2 is a fragmental left side view of the structure shown in Fig. 1 and illustrating the parts in their positions when the space bar is almost fully depressed and the initial or partial escapement action has taken place; and

Fig. 3 is a view similar to Fig. 2 except illustrating the parts in their positions with the final escapement action completed.

The invention has utility in various forms of typewriters; and it is to be understood that, although only those parts necessary for an understanding of this invention have been illustrated in detail, the typewriter mechanism as a whole includes all those parts requisite to a complete typewriter, including a traveling paper carriage, a platen and type bars.

Escapement mechanism

40 The escapement mechanism is operative under the control of the character keys (not shown) and the space bar 10 to cause the paper carriage (not shown) to space toward the left a predetermined distance. This invention has to do mainly with the control of the escapement mechanism by the space bar wherefore operation of the escapement mechanism by the character keys will not be referred to in detail.

50 The escapement mechanism illustrated in Fig. 1 includes an escapement wheel 20 supported by a shaft 21 which is rotatably supported in any suitable manner. The escapement wheel 20 is drive-connected to the shaft 21 by an internal pawl (not shown). The shaft 21 supports a pin-

ion 22 that is in constant mesh with a rack 23 carried by the paper carriage (not shown) which may be driven in the direction of the arrow (Fig. 1) by the usual spring-drum structure (not shown) or other suitable means. With this arrangement the escapement wheel 20 is constantly urged in clockwise direction to space the carriage toward the left as viewed from the front of the typewriter, but movement of the escapement wheel 20 in this direction is opposed by a pair of escapement dogs 24 and 25.

The escapement dogs 24 and 25, the first of which is movable and the other fixed, as will be well understood, are carried by an escapement block 26 rigidly secured to a shaft 27 having its opposite ends journaled in any suitable fashion in the frame work (not shown) of the machine. Escapement movement of the carriage is permitted by rocking motion of the escapement block 26 under the control of the shaft 27.

20 The escapement dogs 24 and 25 are mounted upon the block 26 in a laterally spaced and offset fashion and the movable dog 24 is normally engaged with the tooth (for example the tooth 28) of the escapement wheel. Rocking movement of 25 the escapement block 26 in counterclockwise direction releases the dog 24 from the tooth 28 permitting the escapement wheel 20 to rotate in clockwise direction into engagement with the stationary dog 25 which, by the said rocking of 30 the escapement block, is moved into the path of the tooth 28. In this manner a partial escapement action is accomplished, the rack 23 and paper carriage being moved to the left a part space. Upon disengagement of the dog 24 from 35 the escapement wheel, a spring (not shown) moves this dog clockwise (as viewed in Fig. 1) to a position directly opposite the space between the escapement wheel tooth 28 and the next succeeding tooth (for example, the tooth 29) so that, 40

when the escapement block 26 is rocked clockwise or restored to its normal position, the escapement dog 25 will be disengaged from the tooth 28 and the spring dog 24 will be moved into active position in front of the next succeeding escapement wheel tooth 29. As the dog 25 is released in the manner stated, the escapement wheel 20 is rotated further in clockwise direction until the succeeding tooth 29 engages the dog 24 and seats the same against the escapement block 45 50 55 26, thus completing a full escapement movement or movement of the paper carriage one full space to the left.

Rocking movement of the shaft 27 by the space bar 10 is accomplished through a lever arm 30

fixed upon the shaft 27. The lever 30, and in turn, the shaft 27 are constantly urged in clockwise direction to normally position the escapement block 26 (Fig. 1) by a spring 31 connected to the upper end of the lever arm and to a suitable fixed support (not shown) on the machine. Rocking movement of the lever 30 in clockwise direction is limited by a stationary, frame-carried stud 32. The forward face of the stud 32 is provided with a flat-contact surface adapted to be engaged by the lower end portion of the lever 30 providing a stop for more positively limiting the escapement block to its predetermined normal position of Fig. 1.

Space bar mechanism

In prior typewriter constructions wherein the character keys and the space bar are depressed and then released in order to accomplish a full escapement action and spacing of the paper carriage, it is quite customary for a speedy operator to depress a character key immediately following a space bar operation and before the carriage escapement action under the control of the space bar has been fully completed. The result of this is that the first letter printed after such an operation is incorrectly spaced. A condition of this character is entirely avoided by this invention in a very simple and inexpensive manner and with the use of a minimum number of operating parts. More particularly, this invention provides for both the partial and full escapement movement of the paper carriage on the downward depression of the space bar and before the latter is released, whereby a complete carriage escapement is effected by the time a character key can be depressed following a space bar operation.

The space bar mechanism includes the space bar 10 supported by a pair of side arms 40 that are fixed to a cross rock shaft 41 journaled in the side frames (not shown) of the machine in any suitable manner. The rock shaft 41 supports an upwardly extending arm 42, the upper end of which, as at 43, is pivotally connected to an escapement operating link 44.

The escapement operating link 44 extends rearwardly in a generally horizontal direction and, at its rear end, is provided with a forked, angular cam-like member 45 that receives a reduced portion 46 of the fixed stud 32. The link 44 is constantly urged upwardly by a spring 47 connected to the forked member 45 and to a stud 48 carried by the escapement operating lever 30, so that the lower fork arm 49 of the member 45 is yieldably urged upwardly into engagement with the stud portion 46. The forked member 45 of the link 44 extends upwardly from the horizontal at such an angle that, as the link 44 is moved forwardly under the control of the space bar 10, the rear end of the link is lowered by the camming action between the angular forked member 45 and the stud 46.

The rear end of the link 44 is also provided with a horizontal, rearwardly-extending branch 50 disposed beneath the cam member 45 and having a lateral extension or lug 51 that is adapted to extend behind the lower end portion of the lever arm 30. In the normal position of the parts, as shown in Fig. 1, the lug 51 is so positioned that it is substantially in engagement with the rear edge of the lever 30 at such a height thereon as to positively engage the same. It will be seen, therefore, that by depressing the space bar 10, the shaft 41 and arm 42 are rocked clockwise and the link 44 is shifted forwardly; and as

the link 44 is thus shifted, the lug 51 engages and rocks the lever 30 in counterclockwise direction to initiate the escapement action and permit a partial escapement movement as hereinabove described.

As the space bar 10 is depressed and the link 44 is shifted forwardly to initiate the escapement action, the camming action afforded by the stud 46 and the forked member 45 moves the rear end of the link 44 downwardly or counterclockwise until the parts reach the position illustrated in Fig. 2 wherein the positive engagement between the lug 51 and the lower end of the lever 30 is substantially released. As the depression of the space bar 10 is continued, and it is fully depressed as shown in Fig. 3, the lug 51 is shifted downwardly still further by the camming action above described to a point below the lever 30. By this action the lever 30 is fully released and it is rocked clockwise under the urge of the spring 31 thereby rocking the escapement block 26 clockwise and restoring the escapement mechanism to its normal position, whereby a full escapement action is completed in the manner above more particularly set forth.

The spacing between the arms 49 and 52 of the forked end 45 or the link 44 is sufficiently great to permit considerable up and down movement of the rear end of the link 44 so that the foregoing action may take place in a free and unrestricted manner. As the lever 30 is restored to normal position with the space bar 10 still in its depressed condition (Fig. 3), the lower end of the lever 30 engaging the upper part of the lug 51 rocks the rear end of the link 44 downwardly to a slightly additional extent, this action being accommodated by the spacing of the forked arms 49 and 52.

When the space bar is released following the foregoing action, suitable spring means (not shown) in addition to the spring 47 moves the latter upwardly and restores it to normal position. As the space bar 10 moves to its normal or raised position, the link 44 is shifted rearwardly to its position wherein the lug 51 is disposed behind the lower end of the lever arm 30 and the spring 47 returns the forked member 45 and the lug 51 to their normal positions shown in Fig. 1.

The operation and advantages of the invention will be readily understood from the foregoing description. Proper escapement action is insured under all key and space bar depression conditions. The proper spacing of the carriage is accomplished upon depression of the space bar regardless whether the space bar is held in depressed condition or is released, and in that case also the continued depression of the space bar does not affect successive operation of the character keys. The advantages first above stated are attained with but very few operating parts that are simply constructed and are reliable and highly efficient in use. Operating speed is materially increased.

It will be understood that while I have shown only one form of structure embodying the invention, other changes in details and arrangement of parts may be made without departing from the spirit and scope of the invention as defined by the claims that follow.

I claim:

1. In a typewriter, escapement mechanism including a lever arm rockable back and forth between predetermined limits to effect a complete escapement movement of said escapement mech-

anism, a depressible space bar, means operated by said space bar to engage said lever arm and rock the latter in one direction to effect a partial escapement movement, means operated by said space bar and including a pair of constantly-engaged cam-acting parts for releasing said first means from said lever arm when said space bar is depressed to a predetermined extent, and means operative independently of said space bar for

rocking said lever arm back to normal position when the latter is released from said first means. 5
5. In a typewriter, escapement mechanism including a rock member rockable back and forth between predetermined limits to effect a complete escapement movement of said escapement mechanism, a space bar, and connections between said space bar and rock member whereby a complete escapement movement is effected upon depression of said space bar, said connections including a 10 link longitudinally shiftable by depression of said space bar, a stationary member, a lug on one end of said link member engageable with said rock member for rocking the latter as said space bar is depressed, a forked member on the end of said 15 link member and straddling said stationary member, said forked member being constructed and arranged to engage said stationary member and shift said link member downwardly as said link member is shifted longitudinally to thereby disengage said lug and rock member as said space bar is depressed, and means rocking said rock member back to normal position when said lug is disengaged therefrom to complete a full escapement movement of said escapement mechanism. 20 25

2. In a typewriter, escapement mechanism including a lever member rockable between predetermined limits to effect one complete escapement operation, a space bar, and means actuated by said space bar for effecting one complete escapement movement upon depression of said space bar including a link member bodily shiftable in longitudinal direction toward the space bar by depression of said space bar, means carried by said link member and engageable with said lever member to rock the latter in one direction when said link member is shifted longitudinally, a stationary cam element, means carried by said link and engageable with said cam element for moving said first means out of engagement with said lever member as said link is shifted in said one longitudinal direction, and means operative independently of said space bar as said first means is disengaged from said lever member for moving said lever member in an opposite direction to its normal position. 30

3. In a typewriter, escapement mechanism including a lever arm rockable between predetermined limits for effecting escapement movement of said escapement mechanism, a stationary cam member, a space bar, and means for effecting escapement movement of said escapement mechanism as said space bar is depressed including a link member shiftable toward said space bar as said space bar is depressed, an actuating element on said link member engageable with said lever arm for rocking the latter in one direction as said link is shifted by depression of said space bar, a cam element on said link member engageable with said cam member as said link member is so shifted for depressing the latter and releasing said actuating element from said lever arm, means for rocking said lever arm back to normal position upon release of said actuating element and while said space bar remains depressed, said actuating element and said lever arm being automatically returned to operative relationship as said space bar is released. 40 45

4. In a typewriter, escapement mechanism, a space bar, a member rockable back and forth to effect escapement movement of said escapement mechanism, a second member shiftable by depression of said space bar, a stationary member, means on said second member positively engageable with said rockable member during a predetermined extent of depression of said space bar, positive means on said second member constantly engaged with said stationary member, and operative as said predetermined extent of space bar depression is exceeded to shift said first means out of engagement with said first member, means operative as said first member and first means are disengaged to rock said first member back to its normal position and complete an escapement movement, and means operative to restore said space bar to its raised position and said first mem- 50 55 60 65 70 75

ber and said first means to their operative positions as said space bar is released. 80

5. In a typewriter, escapement mechanism including a rock shaft having a rock arm projecting therefrom and rockable back and forth between predetermined limits to effect a complete escapement movement of said escapement mechanism, a space bar, a link connected to said space bar for longitudinal shift movement as said space bar is depressed, a lateral lug on the end of said link disposed normally behind the end portion of said arm and adapted to engage and rock the latter in one direction to effect a partial escapement movement as said link is shifted, a stationary cam element, another cam element on the end of said link adjacent said lug and engaged with said stationary cam element to shift said lug toward and beyond the end of said arm as said link is shifted, and means rocking said arm back to normal position as said lug is moved beyond the end of said arm to effect a complete escapement movement. 85 90 95

7. In a typewriter, escapement mechanism including a rock shaft having a rock arm projecting therefrom and rockable back and forth between predetermined limits to effect a complete escapement movement of said escapement mechanism, a space bar, a link connected at one end to said space bar and having its other end projected horizontally and terminating in an upwardly turned forked portion having vertically spaced fork arms, a stationary member aligned with the horizontal portion of said link and received within said forked portion, means yieldably urging the lowermost of said fork arms into engagement with said stationary member, a branch member on the end of said link beneath said forked portion and having a lateral extension projecting behind said rock arm for rock movement of the latter as said link is shifted by depression of said space bar, said forked portion of the link and said stationary member operating to shift the adjacent end of said link downwardly and to disengage said lateral extension and rock arm as said space bar approaches its fully depressed condition, and means rocking said rock arm back to normal position as the latter is released from said lateral extension to complete the escapement movement while said space bar remains depressed. 100
